UNITED STATES PATENT OFFICE.

HENRY OSGOOD NOYES AND BLAINE KITZMILLER, OF OAKLAND, CALIFORNIA; SAID KITZMILLER ASSIGNOR TO SAID NOYES.

COIN-CONTROLLED VENDING AND GAME DEVICE.

Application filed April 16, 1923. Serial No. 632,309.

To all whom it may concern:

Be it known that we, HENRY Osgood NOYES and BLAINE KITZMILLER, citizens of the United States, residing at Oakland, in 5 the county of Alameda and State of California, have invented certain new and useful Improvements in a Coin-Controlled Vending and Game Device, of which the following is a specification.

10 This invention relates to coin-controlled vending devices; and it consists in the novel construction, arrangement and combination of parts, hereinafter described and later claimed.

15 The object of our invention is to provide a device of the above type which will stimulate sales of the commodities displayed, by coupling with the vending of such merchandise an element of entertainment and recreation. We further aim, through our invention, to increase the efficiency of devices of 20 this type as silent salesmen, and to increase the volume of business transacted by such devices.

25 The structure herein described is suited, as a vending device, for dispensing merchandise spherical in form, such as candy marbles or licorice balls; it is suited, as a game, for play by one to five players.

30 In order that our invention may be clearly understood and readily carried into effect, the same is hereinafter described with reference to the accompanying drawings, in which similar numerals indicate like parts:

35 Of such drawings,

Fig. 1 is a front elevation of our device.

Fig. 2 is an elevation of one side thereof.

Fig. 3 is a sectional plan view, showing delivery cup and coin box.

40 Fig. 4 is a horizontal section, partly broken away, taken on a plane below the compartments.

Fig. 5 is a horizontal sectional plan view of our device with the top removed.

45 Fig. 6 is an enlarged detail, in section, of the chaseway.

Fig. 7 is a vertical cross sectional view of the device taken through its center.

50 Fig. 8 is a sectional plan view, showing interior of bowl partially broken away to disclose the baffle-board.

Fig. 9 is a vertical cross section through the turret and coin-cabinet.

55 In detail our construction is as follows:

Suitably supported below the top, 2, of a

square cabinet, 3, are compartments, 4, for candy balls, 5. These compartments are filled through openings, 6. Radiating from a block, 7, in the upper central portion of the cabinet are downwardly inclined roofed 60 sunken chaseways, 8, through which the balls are fed into the device. There is one such chaseway for each compartment. The bottom, 9, of each chaseway terminates on a plate, 10, supported by cleats attached to 65 the cabinet. Said plate, 10, below each compartment is provided with openings, 11, through which the balls at the lower ends of the chaseways may drop. Each dropped ball comes to rest on a movable shelf, 12, 70 loosely mounted on a rod, 13, imbedded at alternate ends in the bottom, 14, of said cabinet and said block, 7. Equidistant from their pivot point and from each other, each shelf, 12, is provided with an opening, 15. 75 Behind each such opening a portion of each shelf is turned up to form a stop, 16. This stop operates to hold in check all balls in the chaseway behind the leading ball therein until after the latter has been released 80 and the releasing mechanism has returned to its neutral position. These shelves, 12, are mounted on said rod one above the other, and are so bent that their outward portions occupy the same plane. Integral with each 85 shelf is an arm, 17, extending outward and terminating in a turret, 18. The roof of said turret is provided with a series of slots, 19, each adapted to receive a coin, 20. Adapted to co-operate with each arm, 17, is a lever, 90 21, also movably mounted on said rod, 13. The free end or handle, 22, of each lever is superimposed on its co-operating arm, and extends outward through a slot, 23, in the side of said turret, 18. Each lever, also, is 95 provided with a slot, 24, coinciding with a slot, 25, in its co-operating arm. (See Fig. 9). A portion of said arm is turned up to form a stop, 26, against which the lever, 21, is held in constant contact by a spring, 27. Within the turret is a floor, 28, provided 100 with a series of slots, 29. Co-operating arms and levers may be locked together by the insertion of a coin, 20, in the slots, 24 and 25. The coin, when first dropped, rests on said 105 floor, 28.

Below said plate, 10, is a disc, 30, movably mounted on said rod, 13, and provided with a series of bottomless cups, 31, neutrally registered with the openings, 11, in 110

said plate, 10, but adapted to coincide with the openings, 32, in a plate, 33, when said disc is operated. Attached to the under surface of said disc is a downwardly projecting bracket, 34, which carries at its lower end a pawl, 35. Said plate, 33, is partially cut away to permit movement of the bracket, 34. To said disc is affixed a suitable lever, 36, projecting outward through a slot, 37, in said cabinet. Below said disc said plate, 33, is suitably supported by cleats; it is also provided with a series of openings, 32, (one of which is shown in dotted lines in Fig. 4) which open into the upper end of downwardly inclined curved chutes, 39, suspended from said plate, 33. Rotatable on said rod, 13, and below the lower ends of said chutes, is a bottomless bowl, 40, whose racheted rim, 41, engages the said pawl, 35. The pressure of the pawl is controlled by a spring, 42. Fixed to said rod below said bowl is a downwardly inclined baffle-board, 43, provided with meandering irregular courses, 44, for said candy balls. Below said baffle-board, and suitably supported by cleats, is a downwardly inclined floor, 45, provided with a circular opening, 46, at its center. Attached to said rod below said floor, 45, is a tilted cup, 47, provided with a downwardly inclined runway, 48, leading into a coverless receiver, 49, on the outside of the front of said cabinet.

A portion of the front, back, and one side of the cabinet is of transparent material, 50, so that the chutes, bowl, baffle-board, and floor, 45, may be seen by the players. Only similarly colored candy balls are placed in the same compartment, and the handle of the lever co-operating with its respective shelf beneath each compartment is colored to correspond with the color of the balls contained therein.

Coins passing through the slots, 29, in the floor, 28, of the turret, 18, are caught in the receptacle, 51, which is provided with a transparent front, 52, through which the attendant may see the character of coins being used by the players. The bottom, 53, of the receptacle is supported on trunnions, 54, and it may be tipped by manipulating the knob, 55, on the end of the rod, 56, attached to said bottom. When the bottom is tipped the coins resting thereon are deposited in the removable drawer, 57, of the coin-cabinet, 58.

Our device is operated and played as follows: Each player deposits a coin in the slot in the turret above the handle similarly colored with the color of the candy ball which he desires to purchase. The dropped coin locks the lever and its co-operating arm. The player then pulls the lever to the left, which causes the shelf that is integral with the arm to radially advance. When

the shelf has been sufficiently advanced, the opening therein registers with the opening in the plate, 10, and the leading ball in the roofed chaseway drops into the bottomless cup, 31, of the disc, 30, and comes to rest on the plate, 33. The stop, 16, by this movement, assumes a position behind the leading ball, and holds immovable all other balls in the compartment. Synchronously with the registering of the respective openings in the arm and plate, 10, the coin drops through the slot, 29, in the floor of the turret,—thereby unlocking the lever and arm. When the player releases the handle, the action of the spring 27, returns the lever to its neutral position, and, as the said lever is in constant contact with the stop, 26, of the said arm, such action also returns the arm to its neutral position. By our construction only one of the candy balls from among those held in reserve in the compartment replaces the ball which is dropped, but no replacement can take place until the stop, 16, on said shelf has been withdrawn when the shelf returns to its neutral position.

After the candy balls of all the players have been deposited in their respective cups, the lever, 36, of the said disc is pulled to the left. Such action causes the balls in said cups to roll on the plate, 33; it also causes the bowl, 40, to spin by reason of the engagement of the pawl with the racheted rim of said bowl. When the disc has been sufficiently moved each bottomless cup will register with its respective opening, 32, in said plate, 33, and all balls in the cups will drop simultaneously into the open upper ends of the chutes, down which each will course and drop into the interior of the whirling bowl. When the lever, 36, is released the action of the spring, 59, returns the disc to its neutral position.

Eventually the balls will fall through the open portion of said whirling bowl and drop on the baffle-board, 43, down which they will roll, being retarded the while by the irregular meandering courses therein. From the nature of its construction, it is obvious that the baffle-board may not necessarily effect any two balls in the same manner. From the baffle-board the balls will drop on the sloping floor, 45, from which they will roll into the cup, 47, then into the curved runway, 48, and finally come to rest in the outside receiver, 49. The players then remove their purchases; and the player whose ball comes first into the receiver wins the game. Every ball played drops into its respective chute synchronously with every other ball played, but on account of the action of the whirling bowl and the baffle-board, it is impossible to pre-determine just which ball from among them will first emerge in the receiver.

We would have it understood that the construction herein illustrated and particularly described is intended to exemplify what is at present regarded to be the preferred embodiment of our invention, and that the invention may be otherwise and variously embodied without departing from its spirit or the scope of the subjoined claims.

10 Having thus described our invention, what we desire to claim and to secure by Letters Patent is:—

1. In a device of the character described, the combination of a receptacle divided into 15 compartments for displaying articles of merchandise on sale, separate coin-controlled mechanisms for placing in playable position one of the number of articles contained in each compartment, actuating means for releasing into play simultaneously with each other all articles previously placed in playable position, and a baffle for irregularly retarding the delivery of the articles released in order to render it impossible to 20 predetermine which one from among them will first emerge from the body of the device.

2. In a device of the character described, the combination of separate compartments 30 for storing articles of merchandise offered for sale, a coin-controlled actuating lever and co-operating arm for placing in playable position within said device one from the number of articles held in each compartment, actuating means for simultaneously 35 releasing into play all articles previously placed in playable position, an impetus imparting bowl, and a baffle for irregularly retarding the passage of said articles through 40 the interior of said device and their delivery therefrom.

3. In a device of the character described, coin-controlled means for placing in playable position one from a number of articles 45 displayed for sale, said means consisting of a movable shelf upon which said articles are received, an arm integral with said shelf, an actuating lever for said arm superimposed thereon, coincident slots in both arm and 50 lever adapted to receive a locking-coin, an escape for said locking-coin, a coin box for used coins, and means for returning said shelf, arm, and lever to their neutral positions after said articles have been placed 55 in playable position.

4. In a device of the character described, a compartment for storing articles of merchandise displayed for sale, a chaseway through which said articles are fed from 60 said compartment, a movable shelf below said chaseway upon which said articles are

received, an arm integral with said shelf, an actuating lever for said arm superimposed thereon, coincident slots in both arm and lever adapted to receive a locking-coin, an 65 escape for said locking-coin, a coin box for used coins, and means for returning said shelf, arm, and lever to their neutral positions.

5. In a device of the character described, 70 the combination of a compartment for storing articles of merchandise on sale, a coin-controlled actuating lever and co-operating arm for placing in playable position one from the number of articles held in said 75 compartment, a disc for releasing into play said playable article, and a baffle for irregularly retarding the downward passage of said article through said device.

6. In a device of the character described, 80 the combination of a display-bin for articles of merchandise offered for sale, coin-controlled means for placing one of said 85 articles in playable position within the body of said device, means for releasing said article into play, and a baffle for irregularly retarding the delivery of said article.

7. In a device of the character described, the combination of a plurality of coin-controlled means for placing in playable position one from a number of articles displayed for sale, means for simultaneously releasing into play all articles that have previously been placed in playable position, and a baffle for irregularly retarding the delivery to the purchasers of said articles released in order to render it impossible to 95 predetermine which one from among them will first emerge from the body of the device.

8. In a device of the character described, a display-bin for articles of merchandise offered for sale, a coin-controlled actuating lever and co-operating arm for placing in playable position within said device one from the number of articles held in said display-bin, a movable disc for releasing into play said playable article, an operating lever for said disc, a stationary plate below said disc, openings in said plate through which articles may drop when said disc is operated, a downwardly extending chute for each of said openings, a rotatable open-bottomed bowl adapted to give impetus to the descending article, and a baffle for irregularly retarding the delivery of said article 100 to the purchaser.

In testimony whereof we have hereunto affixed our signatures.

HENRY OSGOOD NOYES.
BLAINE KITZMILLER.
